UNITED STATES PATENT OFFICE.

EDMOND FILLETTAZ, OF LYON, FRANCE.

STARTING MECHANISM FOR EXPLOSION-MOTORS.

1,083,929.

Specification of Letters Patent. Patented Jan. 13, 1914.

Application filed August 2, 1912. Serial No. 712,867.

To all whom it may concern:

Be it known that I, EDMOND FILLETTAZ, a citizen of the French Republic, residing at Lyon, in France, have invented certain new and useful Improvements in Starting Mechanism for Explosion-Motors, of which the following is a specification.

The mechanism which forms the object of the present invention is for starting explosion motors from a distance. The invention is applicable for motors of all kinds and for all uses, such for instance as fixed motors, car and boat motors, motors for aviation purposes, etc.

The invention is characterized by the combination with an auxiliary shaft arranged on the same axis as the motor shaft, with pawl and ratchet mechanism operated from a distance by means of a transmission means comprising a cord or cable and levers and with an automatic unclutching device which disconnects the motor shaft from the auxiliary shaft immediately the motor has started.

The annexed drawing illustrates a form of construction of the invention intended to be installed on a motor car.

Figure 1 is a side view of the whole of the device. Fig. 2 is an end view partly in section on line II—II of Fig. 1. Fig. 3 is a section on an enlarged scale on line III—III of Fig. 2. Fig. 4 is a front view of the interior of the pawl gear which starts the motor. Fig. 5 is a section on line V—V of Fig. 3 of the automatic unclutching device of the auxiliary shaft. Fig. 6 illustrates another form of construction of the pawl gear. Figs. 7 and 8 are longitudinal and transverse sections respectively of another form of construction of the automatic clutch.

The crank sleeve 1 of the car (or any other analogous part if the apparatus is not applied on a motor car) is provided with a shaft 2 which carries a divided boss 3 mounted on a threaded support. The head 2^a of this auxiliary shaft 2, which is situated in alignment with the motor shaft 4, is provided with longitudinal channels 5 of semi-circular section and engages in a cup 6 fixed to the end of the motor shaft 4. This cup is provided with deep recesses 7 equal in number to the channels 5 of the head 2^a, and in each of said recesses a ball 8 is housed.

Around the boss 3 is a collar 9 provided

interiorly with teeth in the form of a ratchet 10 (Figs. 3 and 4) with which pawls 11 carried by the boss 3 engage. The collar 9 is mounted on balls and has an arm 12 by means of which it can be given a rotary movement which if it is executed in the direction of the arrow a (Figs. 2 and 4) causes the shaft 2 to turn by reason of the engagement of the pawls 11 with the ratchet 10, while in the reverse direction the movement of the collar 9 has no effect on this axle. The collar 9 is constantly submitted to the action of a spring 13 surrounding the shaft 2 and tending to return it to its initial position shown in full lines in Fig. 2. The ends of the spring are respectively fixed to the sleeve 1 and to the arm 12 of the collar as shown in Fig. 3. The torsion of this spring draws the arm 12 backward when it is free.

The shaft 2 being rotated as has been explained, rotates the motor shaft 4 by means of the balls 8, some of which are always wedged between the ends of the channels 5 and the sides of the recesses 7 as shown in Fig. 5. This wedging action operates while the motor is not working, but immediately it is started and attains a certain speed, all the balls 8 are thrown to the ends of the recesses 7 by the action of centrifugal force, so that the motor shaft is independent of the shaft 2 which thus remains immovable during the action of the motor.

The operation of the collar 9 is effected by means of a cord or cable 14 attached to a button 15, the position of which is regulatable along a guide 16 made in the arm 12. The cord 14 passes over a pulley 17 (Figs. 1 and 2), the spindle of which is articulated at any point of the frame or the axle tree of the vehicle in order that the pulley may follow the variations of inclination of the cord 14; this cord is suitably conducted along the frame of the car and its other end is attached to a lever 18, Fig. 1, fixed on an axle 19 which carries a toothed sector 20. A strong spring 21 is also fixed to the lever 18, the other end of which is attached to a fixed point; this spring is for the purpose of maintaining the cord constantly stretched and for absorbing the force due to the accidental backward movement of the motor. The sector 20 engages with a second sector 22 mounted on an axle 23 carrying a lever 24 arranged near the driver and by means of which the mechanism is put in action.

This toothed sector mechanism allows of actuating the mechanism by a forward and backward movement of the actuating lever 24. Further it allows of obtaining a long stroke of the arm 18 with a relatively small angular displacement of the lever 24.

To put the motor in action the lever 24 is pushed to the end of the forward course which has the effect of moving the lever 18 10 to the position shown in full lines in Fig. 1 and of stretching the spring 21; the cable 14 is then only submitted to the tension of the spring 13 surrounding the shaft 2 in acting on the arm 12, which tension is sufficient to 15 prevent the cord fluctuating. The lever 24 being drawn sharply backward, the lever 18 moves from the position shown in full lines to that shown in dotted lines (Fig. 1), thus exercising traction on the cord to which is 20 added the traction arising from the tension of the spring 21. This traction is transmitted to the arm 12 of the collar 9 which causes the shaft 2, as well as the motor shaft 4, to rotate, clutched in the manner before indicated. A single impulsion is generally sufficient to make the motor rotate sufficiently 25 to cause an explosion, but the same operation can be repeated several times if the motor does not start immediately. Immediately 30 the motor is working and attains a certain speed, the action produced by the balls 8 ceases automatically as has been explained; the shaft 2 ceases to rotate and the pawl and ratchet gear remains at rest.

35 The described mechanism can vary in its details of construction. The cord and toothed sector actuating mechanism can be modified or suppressed in the application if it is possible to attach the cord directly to the actuating lever 24. In this case the spring 21 will be fixed on the lever 24. Also the pawl and ratchet clutch could be replaced by that shown in Fig. 3, which comprises balls or rollers 25 adapted to be 40 wedged between inclines of the boss 3 and the circular hollowing of the collar 9. The unclutching mechanism, operated by the action of centrifugal force, can also be modified, for instance, as shown in Figs. 7 and 8, 45 the channels 5^a of the shaft 2 are rectangular and the cup 6 of the motor shaft 4 is provided with two bolts 26 engaged in the channels 5^a by springs 27. When the motor turns, the centrifugal force separates the 50 movable parts which produces the disengagement of the motor shaft and auxiliary shaft. Each of these devices can be employed with 55 the one or other of those described previ-

ously, or in combination with any other mechanism operating on the same principles. 60

What I claim as my invention and desire to secure by Letters Patent of the United States is:—

1. In starting mechanism for explosion motors, the combination of the motor shaft, 65 an auxiliary shaft arranged on the same axis as the motor shaft, means for clutching said auxiliary shaft with the motor shaft and for automatically unclutching the same when the motor has started and attained a certain 70 speed, a collar on said auxiliary shaft, a ratchet within said collar, a divided boss on said auxiliary shaft, pawls carried by said boss engaging with the teeth of said ratchet, an arm on said collar, a spring surrounding 75 said shaft and engaging said collar and adapted to yieldingly hold the collar in normal position, a cord attached to said arm for imparting a rotary movement to said collar and to said auxiliary shaft in the one direction, and a spring for tensioning said cord. 80

2. In starting mechanism for explosion motors, the combination of the motor shaft, 85 an auxiliary shaft arranged on the same axis as the motor shaft, a channeled head on said auxiliary shaft, a cup on the end of the motor shaft in which said head engages and provided with relatively deep recesses equal in number to the channels in said head, members movable within said channels and 90 adapted to lock said head and said cup together or to be thrown by centrifugal force into the recesses of said cup to free the head of the auxiliary shaft therefrom when the motor has started, a collar on said auxiliary 95 shaft, a ratchet within said collar, a divided boss on said auxiliary shaft, pawls carried by said boss engaging with the teeth of said ratchet, an arm on said collar, a spring surrounding said auxiliary shaft and fast at 100 one end and having its other end engaging said collar, a cord attached to said arm for imparting a rotary movement to said collar and to said auxiliary shaft in the one direction, a spring for tensioning said cord, a 105 lever attached to the free end of said cord, a sector on said lever, an operating lever and a sector thereon coacting with the afore- said sector for operating the cord.

In witness whereof I have signed this 110 specification in the presence of two witnesses.

EDMOND FILLETTAZ.
